UNITED STATES PATENT OFFICE.

BURT S. HARRISON, OF CHICAGO, ILLINOIS, ASSIGNOR TO DRYING SYSTEMS, INC., OF CHICAGO, ILLINOIS, A CORPORATION OF ILLINOIS.

AIR CLEANER.

Application filed October 8, 1924. Serial No. 742,433.

To all whom it may concern:

Be it known that I, BURT S. HARRISON, a citizen of the United States of America, and a resident of Chicago, county of Cook, 5 and State of Illinois, have invented a new and useful Improvement in Air Cleaners, of which the following is a specification.

This invention relates to air cleaners of the class utilizing an oiled surface over 10 which the air to be cleaned is caused to pass. Thus, substantially all dirt, dust and lint is removed from the air by adhering to the oiled surfaces. To maintain the desired efficiency of such air cleaners it is necessary 15 in some manner to remove the dirt collected by the cleaner. One way of doing this is to cause the cleaning surface to slowly but continuously move through a bath of oil. Such construction necessitates a driving mechanism, including a reduction gearing adapted 20 to bring about a great reduction in speed, and a comparatively costly construction of the cleaning element, for example, a chain affair comprising numerous parallel corrugated links and sprockets for driving it 25 through the oil and through the current of air.

The purpose of the present invention is to provide an air cleaning device equal in 30 efficiency to the above mentioned prior type of device, and utilizing the same efficient cleaning principle, but avoiding the necessity of being continuously driven, and other costly arrangements incidental to the prior 35 structure.

The purpose of the invention may be accomplished by a construction as illustrated in the drawing, in which—

Figure 1 is a view in front elevation of 40 the improved air cleaner.

Fig. 2 is a sectional view taken on the line 2—2 of Fig. 1.

Fig. 3 is a sectional detail taken on the line 3—3 of Fig. 2.

The construction as illustrated is installed 45 in an air conduit. This conduit may be the fresh air intake to a building or used for recirculating reconditioned air which is more or less continuously reused in order to save the heat therein. The invention is 50 widely useful, one of the most important uses thereof being for cleaning the air used in cooling electrical generators, motors and rotary transformers, it being necessary to prevent inflammable lint from collecting

around such machines. The most dangerous dust is often too light to be removed from the air by other devices than those employing some means for causing the dust to adhere to a sticky surface. The present invention 60 meets such requirements in a simple way, and is also equally as well suited for removing comparatively heavy particles of dust from the air, such as the dust from grinding machines or explosive particles of 65 carbon where coal is handled and treated, or other dust-like substances which might be floating in the air.

One preferred form of the construction 70 comprises a rectangular casing having an air inlet and an air outlet which may be coaxial, and between which are arranged a large number of parallel plates extending in the direction of the air current, but bent back and forth to provide a plurality of 75 zig-zag narrow passageways for the air. At the bottom of the casing is an oil container, and means are provided for pumping the oil from the oil container to the top of the casing, where it is sprayed downwardly over 80 the dust eliminator plates. This spraying arrangement is only utilized intermittently, that is, for a few minutes at the end of any period of hours, such as four, eight or twelve, at which time the air inlet and outlet 85 openings of the apparatus are closed to the air conduit in order to prevent particles of the oil being blown along with the air. The mere film of oil on the eliminator plates will not be blown off by the air traveling 90 at the normal velocities in most air circulating circuits. When the eliminator plates are washed clear of used oil and are re-surfaced with fresh oil, the used oil drops back into the oil container where it is allowed to 95 settle and is drained from time to time, and possibly re-filtered and used over again.

The construction as above referred to is shown in the drawing as follows:

The casing 1 is shown as passing through 100 an air conduit 2 with openings substantially the size of the conduit at 3 and 4. Mounted within the casing 1 between the openings 3 and 4 is a large number of parallel eliminator plates 5, preferably bent 105 to the form indicated in Fig. 3. These plates serve to cut the column of air into a plurality of narrow divisions, and cause these divisions of air to move from side to side while passing through the eliminator 110

and to roll out along the oiled surface thereof. Substantially all dust-like or liny impurities in the air adhere to the oil film on the eliminator. Under average working conditions it is only necessary to renew the oil film once or twice a day. When this is done the pivoted shutters or louver arrangement 6 and 7, mounted within the frame surrounding the openings 3 and 4, 10 are shifted to close these openings. Then an electric motor 8 is started, and the oil pump 9 driven by the motor serves to pump oil out of the tank 10 at the bottom of casing 1, and discharge it through the conduit 11 to the spray 12 mounted in a housing 13 at the top of the device. The dirt laden oil is thus washed off the eliminator 15, and the plates of the eliminator are left with a fresh charge of oil when the motor 20 is stopped. The shutters 6 and 7 are operated by a common handle 14, connected to the shutters by the bell cranks 15 and links 16, as shown in Fig. 1.

The operation of the device in respect to 25 removing the dust from the air is much the same as with other apparatus of the same general class in that the air is divided into a plurality of separate more or less sheet-like streams, which are caused 30 to travel back and forth over a wrinkled or corrugated oiled surface, the dust adhering to such surface while the travel of the pure air is not much interfered with.

In respect to cleaning the surfaces of the eliminator, the operation is different, as in the present case the eliminator is stationary and is bathed from time to time by an oil spray, at which time the louver arrangement is closed. A light or medium mineral lubricating oil is generally employed in most uses of the apparatus, as such oil is sufficiently adhesive and is heavy enough not to be blown along with the air. 35 40

Although but one specific embodiment of this invention has been herein shown and described, it will be understood that numerous details of the construction shown may be altered or omitted without departing from the spirit of this invention as defined by the following claim. 45 50

I claim:

An air cleaning device of the class described, having an air passageway extending therethrough, said air passage being divided by a plurality of parallel bent eliminator plates so formed as to divide a current of air into a plurality of separate currents and cause such separate currents to oscillate from side to side while passing the eliminator plates, means for spraying said eliminator plates with a dirt collecting liquid, and means for preventing air from passing through said device during the spraying operation. 55 60

Signed at Chicago, this 2 day of Oct. 1924.
BURT S. HARRISON.
